COIN DETECTOR

Frank H. Vogel, Columbus, Ohio, assignor to The
Columbus Vending Company, Columbus, Ohio,
a corporation of Ohio

Application May 3, 1940, Serial No. 333,172

12 Claims. (Cl. 194—97)

My invention relates to a coin detector. It has to do, more particularly, with a coin detector adapted to be applied to a coin operated vending machine in order that it will detect spurious magnetic coins or slugs, coins or washers having a hole in them, light weight coins or tokens or other light weight objects, and even very thin coins or slugs, and prevent such spurious coins from reaching the operating mechanism of the vending machine.

One of the objects of my invention is to provide a coin detector which is of such a nature that it will effectively detect spurious coins or slugs of the type indicated above.

Another object of my invention is to provide a coin detector of the type indicated which is of such a nature that after a spurious coin has been detected and prevented from reaching the operating mechanism of the vending machine, it may be easily and effectively cleared from the coin detector.

Another object of my invention is to provide a coin detector of the type indicated which is of such a nature that after a spurious coin has been detected and prevented from reaching the operating mechanism of the vending machine, and in case several other spurious coins or good coins are put into the detector before the first spurious coin has been cleared, not only the first one but all succeeding ones, even the good coins, may be easily, quickly and effectively cleared from the coin detector.

Another object of my invention is to provide a coin detector of such a nature that any coin, either good or bad, will be quickly cleared therefrom before reaching the coin controlled mechanism of the machine with which it is associated, upon the slightest movement of the actuating lever or other actuating member of the machine and, therefore, to actuate the machine it will be necessary to insert a good coin and permit it to reach the coin controlled mechanism of the machine before actuating the lever.

Another object of my invention is to provide a coin detector of the type indicated which is very simple and compact, which may be readily taken apart, and which is of a very rugged construction.

Another object of my invention is to provide a coin detector embodying a compact single unit which may be applied readily to various types of vending machines now commonly in use.

In its preferred form, my invention contemplates the provision of a coin detector which is in the form of a compact unit which may be asso-

ciated with any suitable type of vending machine. This detector comprises a unit in which three separate vertically disposed plates are provided. These plates include a rigid back plate, a movable middle plate and a movable front plate. The middle plate and front plate are hinged to the back plate at the upper end thereof. The back plate carries a plurality of integrally formed ledges which extend through corresponding openings in the middle plate and which normally contact with the inner surface of the outer or front hinged plate. When the detector is in its normal closed condition with the three plates disposed closely adjacent each other, the ledges, extending through the middle plate from the rear, form a channel for the coins, between the front and middle plates, extending from the top to the bottom of the coin detector. Good coins of the proper size will freely pass through this channel, 15 The back plate carries an escapement of novel construction and design, for detecting a slug or washer with a hole in it, also for detecting a slug or spurious article or token that is lighter in weight than a good coin. Said escapement is 20 mounted in or upon the back plate in a vertical position and projects forwardly through openings in the middle and front plate, which openings are located at the center portion of one of the vertical channels through which the coins must 25 pass when traveling downward through said channel. This escapement is of such a nature and is loosely pivoted so that it will be moved out of the channel by a good coin but will project through the opening into a slug or washer to 30 prevent such slug or washer from moving farther through the channel. Also, in the case of a slug or spurious article or token that is lighter in weight than a good coin, said escapement will not move out of the channel but will thus halt and 35 prevent such light weight slug and spurious article or token from moving farther through the channel. The back plate also carries a magnet 40 which has its poles disposed in openings in the middle plate which are located adjacent the coin channel. This magnet will serve to interrupt movement of magnetic slugs through the coin channel. One of the ledges which forms the lower wall of a horizontal portion of the coin channel, is cut away to form a thin slot through which thin coins or slugs will drop or will be 45 halted in their movement.

I provide means for moving the plates relative to each other to clear all of the spurious coins or slugs from the coin channel when they have 50 been detected and stopped in their travel through

the detector. Any good coins inserted after a spurious coin has been detected will also be removed. This means serves to first move the two hinged plates simultaneously so that the middle plate will quickly move away from the back plate, thus clearing the lower ledge first, and then to move the front plate relative to the middle plate. This withdraws all of the ledges from between the middle plate and the front plate so that the space between these two plates will be entirely clear of obstructions. Therefore, all of the coins or slugs will drop from the space between these two plates into a reject chute whence they are returned to the outside of the machine.

The preferred embodiment of my invention is illustrated in the accompanying drawings wherein similar characters of reference designate corresponding parts and wherein:

Figure 1 is a front elevation, partly broken away, of a coin detector made according to my invention.

Figure 2 is a view illustrating the housing of the detector in vertical section but showing the remainder of the detector mainly in side elevation.

Figure 3 is a perspective view, partly broken away, of the detector showing the plates thereof closely adjacent each other, which is their normal position.

Figure 4 is a perspective view, partly broken away, showing the plates of the detector in spaced relationship.

Figure 5 is a horizontal sectional view taken substantially along line 5-5 of Figure 1.

Figure 6 is a detail, mainly in vertical section, showing the escapement device, in the position it occupies after it has interrupted movement of a light weight coin or token through the coin channel.

Figure 7 is a similar view showing a good coin passing the escapement device.

Figure 8 is a similar view showing a washer with a hole in it being engaged by the escapement device to interrupt its movement through the coin channel.

Figure 9 is a similar view but showing the middle and front plates of the detector being moved in order to free the washer from the escapement device.

Figure 10 is a perspective view of a vending machine showing my coin detector in position therein.

Figure 11 is a front elevation of a modified form of my coin detector.

With reference to the drawings, I have illustrated my coin detector as comprising a housing 1 which is adapted to be vertically disposed. Within this housing and secured to the rear wall thereof is a back plate 2. This plate 2 is attached to the rear wall of the housing by means of screws 3 which pass through the rear wall and which extend into lugs 4 secured to the back plate 2 at the upper ends thereof. The lugs 4 extend transversely of the plate 2 and serve to keep the plate 2 in spaced relationship to the rear wall of the housing. This structure is illustrated best in Figure 3 which shows the rear side of the plate 2.

Integrally formed on the front surface of the back plate 2, as illustrated in Figures 1 and 4, is a plurality of ledges or ribs which serve to produce a coin channel, as will be hereinafter apparent. One of these ledges comprises a slightly inclined upper portion 5 disposed adjacent the top of the back plate 2, and a vertical portion 75

6, disposed along one edge of the back plate. The other of the ledges comprises an oppositely inclined portion 7, disposed at a lower level than the portion 5 and adjacent the opposite edge 5 of the back plate 2, and a vertical portion 8, disposed in parallel relationship with the portion 6 and also being spaced a substantial distance from the opposite edge of the back plate 2. The lower edge of the back plate 2 is provided with a ledge 9, which is inclined downwardly in a direction opposite to the direction of inclination of the ledge portion 7.

A middle plate 10 is disposed in front of the plate 2 and normally is adapted to be disposed closely adjacent the back plate. This middle plate has a pair of spaced lugs 11 integrally formed at its upper end. A pin 12 passes through these lugs and through a pair of lugs 13 formed on the upper edge of the back plate 2. Thus, the middle plate 10 has its upper end hinged to the back plate 2. The middle plate 10 is provided with slots 5a, 6a, 7a and 8a which are so disposed that they will receive the portions 5, 6, 7 and 8, respectively, of the ledges formed on the front surface of the back plate 2, when the two plates are in cooperative relationship. The middle plate 10 is further provided on each of its vertical edges with a rearwardly extending flange 14. These flanges extend rearwardly over the side edges of the back plate 2.

I provide a third plate 15, which may be termed the front plate, and which is disposed in front of the plate 10. This plate 15 is provided with a pair of lugs 16 formed at its top corners and which also receive the hinge pin 12. Thus, the upper end of the plate 15 is also hinged to the back plate 2. This plate 15 is provided at one of its side edges with a vertically disposed rearwardly projecting integral flange 17 which extends rearwardly beyond the edges of the plates 10 and 2. At its opposite edge, the plate 15 is provided with an integral vertically disposed flange 18 which also extends rearwardly over the edges of the plates 10 and 2. This flange 18 terminates at a point 19, spaced below the upper edge of plate 15, for a purpose which will be explained later.

A coil spring 20 surrounds the hinge pin 12 and is provided with a pair of depending leg portions 21, one of which engages the rear surface of the back plate 2, passing through a recess in the upper lug 4, and the other of which engages the front surface of the front plate 15. This spring normally tends to hold the plate 15 in contact with plate 10 and the plate 10 in contact with the back plate 2. When the plates are disposed in this relationship, the various portions 5, 6, 7 and 8 of the ledges on the back plate 2 project through the various openings 5a, 6a, 7a and 8a and contact with the rear surface of the front plate 15. The inclined ledge 9 on the lower edge of the plate 2 projects beneath the middle plate 10 and contacts with the rear surface of the front plate 15. This produces a coin channel between the middle plate and the front plate 15 which, as shown in Figure 1, embodies a downwardly inclined portion 22, a vertical portion 23, an oppositely inclined portion 24, a main vertical portion 25 and an inclined portion 26, which is inclined in a direction opposite to the direction of inclination of the portion 24. The flange 18 terminates at the point 19 so as to provide a slot through which the coin may be passed between the plates 15 and 10 so that it will enter into the upper end

of the coin channel. If the coin is a good coin, it will pass through the coin channel and will ultimately roll down the inclined ledge 9. A coin guide 27 (Figures 3 and 4) is provided for receiving the good coin and directing it downwardly into the coin receiving chute 28 which has a flared end 29 disposed directly below the guide 27. This chute 28 will conduct the coin to the operating mechanism of the vending machine. The guide 27 comprises a laterally extending lug 30 formed on one edge of the back plate 2. This lug 30 is provided with a shoulder portion 31 on its outer edge to which a leaf spring 32 is secured in parallel relationship to the main portion of the lug. Thus, a coin receiving guide channel 33 is provided which is directly above the chute 28.

As previously indicated, I provide means for detecting and interrupting passage through the coin channel, of spurious magnetic coins or slugs, coins or washers having a hole in them, coins or tokens or other articles lighter than a good coin, and even very thin coins or slugs, in order to prevent such spurious coins from reaching the operating mechanism of the vending machine.

For detecting and interrupting passage of a coin or washer with a hole in it or a light weight coin or token, I provide the structure illustrated best in Figures 3 and 6 to 9, inclusive. This structure comprises a pivoted escapement member 34 which is associated with the main vertical portion 25 of the coin channel. This escapement member 34 is of the shape shown in Figures 6 to 9. It is carried by a pin 35 which extends through an opening 36 formed therein. The pin 35 extends transversely of a vertical slot 37 formed in the back plate 2 and is carried by this plate. An aligning slot 38 is formed in the middle plate 10. Thus, the escapement 34 is mounted for pivotal movement, within the openings 37 and 38, substantially normal to the plane of each of the plates 2 and 10. The escapement member is normally in the position indicated in Figures 1, 2 and 6.

The shape of the opening 36 in the escapement 34 is very important, as is the outline of the escapement itself. The opening is substantially egg-shaped, or oblong, being wider towards its lower end than towards its upper end. The escapement 34 normally hangs in the position indicated in Figure 6 with its lower edge in contact with the lower end of slot 37. It is provided with an upwardly directed finger 39 which is adapted to be projected into the opening in the coin or slug moved into association with the escapement. It is also provided with a cam finger 40 which normally projects laterally across the coin channel and into a vertical slot 41 formed in the front plate 15. The distance between the centers of the two fingers 39 and 40 is preferably the same as the radius of a coin of the proper size. Also, the lower portion of the escapement 34, that is the portion below the pivot pin 35, is heavier than the upper portion so that it will normally be in the position indicated in Figure 6.

When a coin or token L which is lighter in weight than a good coin adapted to operate the machine, drops through the coin channel, it contacts with the upper edge of the finger 40 but will be of insufficient weight to swing the escapement member about the pivot 35. Therefore, further movement of this light weight coin or token through the coin channel will be precluded, as shown in Figure 6. The lower portion

of the escapement member is of a preselected weight so that only a coin of proper weight will swing the escapement member about its pivot.

When a good coin C passes this escapement device, the escapement will be operated in the manner illustrated in Figure 7. The coin will strike the upper edge of the cam finger 40. It will swing the escapement about the pivot pin 35, in the manner illustrated in Figure 7, and finally the face of the coin will engage the outer end of the finger 40. This swings the finger 39 out into the coin channel and into contact with the face of the coin. However, since the coin is solid, further outward movement of the finger 39 is prevented. The opening 36 is of such shape and size that the fingers 39 and 40 will merely project slightly into the coin channel, as indicated in Figure 7, but will not prevent passage of the good coin by the escapement device.

When a coin or washer W with a hole in it moves into association with the escapement member, as indicated in Figure 8, it first engages the upper edge of the cam finger 40. This causes the escapement member 34 to swing about its pivot and causes the finger 39 to swing into the coin channel. The lower portion of the washer then engage the outer portion of finger 40 and forces the finger 39 into the opening in the washer and into the opening 41 and simultaneously moves the entire escapement member to the right (Figure 8) so that the pin 35 will be in the opposite side of the opening 36. The momentum of the washer striking finger 40 is sufficient to project the finger 39 into the opening 36 in the washer. It will be apparent that when the finger 39 once enters into the opening in the washer, the weight and momentum of the washer will tend to swing the finger 39 downwardly farther into the opening in the washer. Thus, this will insure that the finger will continue to project into the opening in the washer and will prevent further movement of the washer through the coin channel.

To release the washer W or the light weight coin L from the escapement member 34, it is necessary to move the plates 2, 10 and 15 relative to each other in the manner illustrated in Figure 9. This is accomplished by means to be described subsequently. This means moves the plate 10 relative to the plate 2 and the plate 15 relative to the plate 10. When the plate 15 moves relative to the plate 10, and the plate 10 is moved relative to plate 2 and the escapement 34, the washer W is moved laterally relative to the escapement 34, as shown in Figure 9, so that the finger 39 is withdrawn from the opening in the washer. Then the washer is free to drop downwardly as indicated in Figure 9. The light weight coin L will be removed in a similar manner.

For detecting and interrupting movement of magnetic slugs through the coin channel, I provide a magnet 42 which is bolted, as at 43, to the back plate 2. This magnet may be a horseshoe magnet and has its ends bent forwardly and extending through pairs of aligning openings 44 and 45 formed in the plates 2 and 10, respectively. It will be noted from Figures 6 to 8 that the inner ends of the magnet are disposed in one wall of the coin channel. It will also be noted that the ends of the magnet are disposed just slightly above the inclined ledge 9, as shown best in Figure 1. When a slug or coin of magnetic material is dropped through the coin channel, it will be stopped by the magnet. At this

time, it will be resting on the ledge 9. When the plate 10 is moved relative to the plate 2, it will sweep the slug from the ledge 9 and move it away from the magnet simultaneously. This will permit the slug to drop from the detector.

For eliminating very thin coins, the inclined ledge 9 has its edge cut away, as indicated at 46 in Figures 2 and 4, for a substantial portion of its length directly below the main vertical portion 26 of the chute. Thus, there will be a thin slot formed between this portion of the ledge and the inner surface of the front plate 15. Consequently, thin slugs tending to roll down the ledge 9, will drop through or halt in this slot.

For moving the plates 2, 10 and 15 relative to each other, I provide the structure now to be described. This structure comprises a flat bar 47 which is carried on the back surface of the back plate 2. This bar is provided with vertical slots 48 and 49 through which bolts 50 and 51 pass. These bolts are threaded into the back plate. Thus the bar is free to move vertically relative to the back plate. The bar is provided with a shoulder 52 which engages a cam shoulder 53 formed on the flange 17 of the front plate 15. The bar is provided with another vertical slot 54, the lower end of which engages a cam portion 55 carried by the middle plate 10. The portion 55 passes through a slot 56 formed in the back plate. A spring 57 secured to the bar 47 and the back plate 2 normally keeps the bar 47 in its lowermost position. A stop 58 is formed on the rear surface of the back plate 2 and limits upward movement of the bar 47 so that the shoulder 52 will not move off the cam shoulder 53.

When the bar 47 is moved upwardly, the end of slot 54 engaging cam portion 55, first swings the two plates 10 and 15 simultaneously about the pivot pin 12. However, at the same time the shoulder 52 is engaging the cam shoulder 53 and will swing the front plate 15 relative to the middle plate 10 about the pivot pin 12. Thus, the plates 10 and 15 are first moved together slightly relative to the plate 2, which serves to sweep off the lower ledge 9 first, and then the plate 15 is moved outwardly relative to the plate 10. As soon as the upward force on the bar 47 is released, the bar will be returned to its original position by spring 57 and the plates 10 and 15 will swing back into their original positions.

As previously stated, my coin detector may be mounted in any suitable vending machine. In Figure 10, I show it mounted in a vending machine 58. This machine has a coin inserting slot formed in a small plate 59. This slot is of accurate size so that only coins of the proper thickness and diameter can be inserted in the machine. The operating mechanism of this machine is not shown but it is actuated by pushing inwardly on a plunger 60. I prefer to have the plate moving mechanism of my coin detector actuated each time the vending machine is actuated. Therefore, the plunger 60 is provided with a cam portion 61 that engages the cam edge 62 formed on the lower end of the bar 47. Thus, each time the plunger 60 is pushed inwardly to operate the vending machine, the bar 47 is moved upwardly so as to move the plates of the coin detector in the manner previously described. The housing 1 of the coin detector is preferably provided with a funnel-shaped lower portion 63 which leads to an outlet opening 64 in the housing of the vending machine. This portion 63 will serve to receive any good coins or spurious

coins, which drop from the coin detector and to return them to the outlet.

It will be apparent that in the operation of my coin detector, if a coin of proper size, weight and material is inserted in the detector, it will pass through the detector and will drop into the chute 28 and be led to the operating mechanism of the vending machine. However, if for any reason, the good coin fails to pass through the 10 coin detector, when the plunger 60 is operated, to operate the vending machine, the plates 10 and 15 of the coin detector will be moved, allowing the good coin to drop from the detector and to be returned to the outlet. If a coin or token 15 of insufficient weight or a washer with a hole in it, is inserted in the machine, it will pass through the coin channels 22, 23 and 24 into channel 25 until it reaches the escapement member 34, which will stop the movement of the light weight coin 20 or washer and prevent it from reaching the operating mechanism of the machine. If a slug of magnetic material is inserted in the coin channel, it will pass through the channel until it reaches the magnet 42 which will interrupt its 25 movement. If a very thin coin or slug is inserted 25 in the machine and is of sufficient weight to pass the escapement member, it will pass through the channel until it rolls down the ledge 9 when it will drop through the slot formed by the cut 30 away portion 46.

As previously indicated, each time the vending machine is operated the plates of the detector will be moved. Consequently, if a light weight coin 35 or washer is present in the detector and is engaged by the escapement member, it will be removed from the escapement member and will drop from the detector. The same is true of a slug engaged by the magnet. Also, if any good coins are present in the detector, due to 40 their interruption by a previously detected spurious coin or slug, they will drop therefrom when the plates are moved. An important feature of my invention resides in the fact that when the plates are moved, all obstructions in the space 45 between plates 10 and 15 are removed. It will be apparent that when the plate 10 is moved outwardly relative to the plate 2, the ledges 5, 6, 7 and 8 and the ledge 9 are withdrawn behind the front surface of the middle plate 10. Thus, 50 the space between the plates 10 and 15 is completely clear. The escapement member is also completely withdrawn from this space.

In Figure 11, I have illustrated a slightly modified form of my invention. This modified 55 form of coin detector is adapted to detect lead slugs or other slugs not having the proper "bouncing" properties when dropped against an anvil. In this instance the various plates are lengthened. The ledge 9a is carried by the back 60 plate and engages the front plate as before. It extends through a slot in the middle plate. The ledge 9a is shortened and is provided with a downwardly extending portion 9b which extends through a slot in the middle plate and engages 65 the face of the front plate. This portion 9b is provided to form an additional vertical portion 65 of the coin channel. Coins or slugs passing into the portion 65 of the coin channel will drop downwardly and strike an inclined anvil 66. If 70 the coin is a good coin it will bounce from the anvil over into contact with a baffle 67 which will direct it into the chute for the good coins. A pivoted wire member 68 is disposed above the baffle 67 to prevent the good coin from jumping 75 too far. A good coin will bounce with sufficient

force to move the wire member 68 about its pivot and will be permitted to pass beyond the member 67. If the coin which hits the anvil is made of lead or other material not having sufficient "bouncing" properties, it will merely drop down through the space between the members 66 and 67 and will not reach the channel for the good coins. Even if it hits the wire member 68, it will not hit it with sufficient force to swing it about its pivot. Thus, it will be apparent that this modified detector will operate exactly as the form previously described, with the exception that it will have the additional function of detecting coins or slugs which have the other necessary characteristics but do not have the necessary "bouncing" properties.

It will be apparent from the above description that I have provided a coin detector having many advantages. It will effectively detect spurious coins or slugs of the type indicated. Furthermore, it will be easily and quickly cleared of any spurious coins which are detected. My device is very simple and compact, may be readily taken apart and is of a very rugged construction. It may be applied readily to various types of vending machines now commonly used.

Various other advantages will be apparent from the preceding description, the drawings and the following claims.

Having thus described my invention, what I claim is:

1. A coin detector comprising a plate having a plurality of ledges carried thereby, a second plate disposed adjacent the first plate and with which the ledges contact, a third plate disposed between said first-named plates, said ledges extending from the first plate beyond the third plate into contact with the second plate so as to form a coin channel between the second and third plates, means for moving said second and third plates relative to said first plate in a lateral direction relative to the planes of the plates to withdraw said ledges from between said second and third plates and behind said third plate, and means associated with said coin channel and carried by said first-named plate for interrupting passage of spurious coins or slugs therethrough.

2. A coin detector comprising a plate having a plurality of ledges carried thereby, a second plate disposed adjacent the first plate and with which the ledges contact, a third plate disposed between said first-named plates, said ledges extending from the first plate beyond the third plate into contact with the second plate so as to form a coin channel between the second and third plates, means associated with said coin channel and carried by said first-named plate for interrupting movement of a slug of magnetic material therethrough, and means for moving said second and third plates relative to said first plate in a lateral direction relative to the planes of the plates so as to eliminate the slug from the detector.

3. A coin detector comprising a plate having a plurality of ledges carried thereby, a second plate disposed adjacent the first plate and with which the ledges contact, a third plate disposed between said first-named plates, said ledges extending from the first plate beyond the third plate into contact with the second plate so as to form a coin channel between the second and third plates, means associated with said coin channel and carried by said first-named plate for interrupting movement of a slug with a hole in it or a slug of insufficient weight, therethrough, and

means for moving said second and third plates relative to said first plate in a lateral direction relative to the planes of the plates so as to eliminate the slug from the detector.

5. A coin detector comprising a back plate having a plurality of ledges carried thereby, a front plate disposed adjacent the back plate, a middle plate disposed between the front and back plates, said ledges extending beyond the middle plate into contact with the front plate so as to form a coin channel between the front and middle plates, means associated with the coin channel and carried by the back plate for interrupting passage of an improper coin therethrough, and means for moving said middle plate relative to said back plate so that said ledges are withdrawn from the space between said front plate and middle plate.

20 6. A coin detector comprising a back plate having a plurality of ledges carried thereby, a front plate disposed adjacent the back plate, a middle plate disposed between the front and back plates, said ledges extending beyond the middle plate into contact with the front plate so as to form a coin channel between the front and middle plates, a magnet carried by the back plate and associated with the coin channel to interrupt movement of a magnetic slug therethrough, and means for moving said middle plate relative to said back plate so that said ledges are withdrawn from the space between said front plate and middle plate and so that the slug is moved away from the magnet.

25 7. A coin detector comprising a back plate having a plurality of ledges carried thereby, a front plate disposed adjacent the back plate, a middle plate disposed between the front and back plates, said ledges extending beyond the middle plate into contact with the front plate so as to form a coin channel between the front and middle plates, a pivoted escapement member carried by the back plate and associated with the coin channel, said pivoted escapement member permitting movement of a solid coin or slug of sufficient weight through the coin channel but preventing movement of a slug with a hole in it or a slug of insufficient weight through said channel, and means for moving said middle plate relative to said back plate so that said ledges are withdrawn from the space between said front plate and middle plate and so that a slug engaged by the escapement member will be moved off of said member.

30 8. A coin detector comprising a back plate having a plurality of ledges carried thereby, a front plate disposed adjacent the back plate, a middle plate disposed between the front and back plates, said ledges extending beyond the middle plate into contact with the front plate so as to form a coin channel between the front and middle plates, means associated with the coin channel and carried by said back plate for preventing movement of certain slugs therethrough, said plates being hinged together at one end, and means for moving said front and middle plates relative to said back plate so that said ledges will be withdrawn from contact with said front plate and behind said middle plate.

35 9. A coin detector comprising a back plate having a plurality of ledges carried thereby, a front plate disposed adjacent the back plate, a middle plate disposed between the front and back plates, said ledges extending beyond the middle plate into contact with the front plate so as to form a coin channel between the front and middle plates,

means associated with the coin channel and carried by said back plate for preventing movement of certain slugs therethrough, said plates being hinged together at their upper ends, means for normally maintaining said plates in cooperative relationship, and cam means for swinging said front and middle plates relative to said back plate and to each other to withdraw said ledges from contact with said front plate to a position behind said middle plate.

9. In a coin detector, a vertically disposed coin channel, an escapement member associated with said coin channel, said escapement member being pivotally mounted in an opening in one of the side walls of the channel, said escapement member having a cam finger and a finger adapted to be projected into an opening in the slug, the pivotal mounting of the escapement member comprising a pin fitting loosely into an elongated opening in the escapement member, said escapement member being normally so disposed that its cam finger projects into the coin channel so that a coin or slug passing through the channel will contact therewith, said escapement member being so arranged that when a coin or slug contacts with said cam finger it will be moved into the coin channel, said opening in the escapement member permitting movement thereof with respect to its pivot and with relation to the coin channel to permit passage of a solid coin or slug of proper weight past both of said fingers.

10. In a coin detector, a coin channel having a vertically disposed portion, an escapement member associated with said portion, said escapement member being mounted adjacent one wall of said channel, said escapement member having an oval-shaped opening through which a pivot pin projects, said escapement member having a counterbalance portion formed on one end, said escapement member having a cam finger which normally projects into the channel and is adapted to be engaged by a coin or slug passing through the

channel and having a second finger which is normally out of the channel but which will be moved into the channel by pivotal movement of the escapement caused when a coin or slug contacts 5 with the cam finger and swings it against the action of said counterbalance portion.

11. In a coin detector, a coin channel having a vertically disposed portion, an escapement member associated with said vertical portion, said 10 escapement member being mounted for pivotal movement in one of the side walls of the channel, said movement being at a direction normal to the face of a coin passing through the channel, said escapement member having an oval-shaped opening through which a pivot pin extends, said escapement member having a cam finger which 15 normally projects into the channel and is adapted to be engaged by a coin or slug passing through the channel and having a second finger which is normally out of the channel but which will be moved into the channel by pivotal movement of the escapement member caused when a coin or slug of proper weight contacts with the cam finger, said cam finger and other finger being spaced apart a distance corresponding substantially to 20 the radius of a coin of the proper size.

12. A coin detector comprising a back plate having a plurality of ledges carried thereby, a front plate disposed adjacent the back plate, a middle plate disposed between the front and back plates, said ledges extending beyond the middle plate into contact with the front plate so as to 30 form a coin channel between the front and middle plates, one of said ledges being inclined from the horizontal and having a slot formed therein for engaging thin coins or slugs, and means for moving said middle plate relative to said back plate so that the ledges are withdrawn from the space between said front plate and middle plate so that 35 the slug engaged by the slot member will be moved off said member.
